ICE BUCKET

William S. Miller, Ottawa, James O. Plankenhorn, Utica,
and Frank Borkowsky, Ottawa, Ill., assignors to The
J. E. Porter Corporation, Chicago, Ill., a corporation of
Delaware

Filed May 1, 1961, Ser. No. 64,982

Term of patent 14 years

(Cl. D44—15)

FIGURE 1 is a perspective view of an ice bucket showing our new design;

FIGURE 2 is an elevational view taken from the right of FIG. 1, the opposite side being substantially the same;

FIGURE 3 is a top plan view thereof, the handle removed for convenience of illustration; and

FIGURE 4 is a sectional view taken along the line 4-4 of FIG. 1.

The characteristic features of our design reside in the combination on the bucket disclosed of the specific angular bail ears in association with the recessed top having a knob centrally disposed thereon, all as shown.

We claim:

The ornamental design for an ice bucket, substantially as shown and described.
